HENRY COWGILL, OF FREDONIA, DELAWARE, ADMINISTRATOR OF THE
ESTATE OF JOHN H. C. COWGILL, DECEASED.

Letters Patent No. 97,481, dated December 7, 1869.

IMPROVEMENT IN SEWING-MACHINE TABLES.

The Schedule referred to in these Letters Patent and making part of the same.

To all whom it may concern:

Be it known that JOHN H. C. COWGILL, now deceased, late of Fredonia, in the county of Kent, and State of Delaware, did in his lifetime invent certain new and useful Improvements in Sewing-Machines, of which the following is a full, clear, and exact description, reference being had to the accompanying drawings, which make part of this specification.

The object of the invention is to bring the sewing-machine into such an improved position relative to the operator as to relieve the operator from the cramped and uncomfortable position now occupied in working sewing-machines, and attended with such injurious effects upon the system and health.

The invention, to this end, consists—

First, in mounting the machine upon an inclined support, or at an angle to the table, instead of having it rest flat, as is now the case.

Second, in making the machine adjustable to a greater or less inclination or angle, as may be desired.

Third, in making the slippers adjustable toward or from the operator.

Fourth, in combining the inclined adjustable table with the adjustable slippers.

The top of the table is hinged to the frame, at its front edge, and provided with means by which it may be raised or lowered, and held at any inclination desired, in substantially the manner used with the lids of pianos, it being only necessary to make the supports firm enough to prevent undue vibration from the motion of the machinery.

Where it is preferred, for convenience, to have a part of the table flat, or in applying this invention to tables already made in the usual way, a false top, A, may be hinged to or simply mounted upon the front of the table, B, and be provided with inclined supports, C C, either adjustable as above mentioned, or fixed at the desired inclination:

The machine is attached (as usual with flat tables) to this movable or fixed inclined top A, and works smoothly, and without any unequal wear from its being thus tilted.

The operator can sit upright, or even lean back, and yet thus have the work and the working-parts of the machine, the needle, the tension, and the feed-plate, &c., all under the same control, and in as favorable view, and as easy reach as when stooping over a flat table, while the different position thus occupied relieves the back, the shoulders, the chest, and the abdomen from the stooping, and the compression, and the constant fatigues and injurious effects that are attendant upon the position heretofore necessarily occupied in operating these machines.

This adjustability requires, of course, that the driving-band should be capable of being lengthened or shortened as the machine is raised or lowered, but this is easily done by a simple provision of flat hooks and eyes, or grommets, or other like obvious means.

A short section of the band may be made removable, instead of having the ends overlap, or different bands may be used for different positions.

As the elevation of the machine raises the work, and necessitates a higher position for the hands and arms in managing it, an arm-supporter or rest, D, is secured to the table at each side of the machine, and projects toward the operator, whose arms are thereby supported comfortably.

These rests may be hinged, and raised or lowered as desired, and adjusted by set-screws, d, and may be folded over upon the table, and out of the way, when the machine is not in use.

Different operators, using the same machine, or the same operator desiring to occupy different positions at different times, can raise or lower the machine at pleasure, to suit, and can still, at any time, use it in its ordinary horizontal position.

It is found desirable, that in connection with this change of position in the machine, the slipper-bar should be conformably adapted, by a change of its position, as well to secure a more natural relation between it and the table, as to relieve the ankle and the muscles of the limbs, and afford a like choice or change of their position.

Two arms or brackets, E, are pivoted on the legs F F, or side-pieces of the table, and depend below the usual level of the slipper-bar G, swinging freely on their pivots, from a perpendicular, forward or backward. The slipper-bar is secured in these brackets.

In or upon each foot of the table, below the line of the slipper-bar, but a little above the lower end of the swinging arms, a curved guide, H, is provided, the arc of the curve corresponding with the movement of the slipper-bar.

A set-screw, h, passes through the swinging arm E, and fits in this groove, in which it travels, or is fixed, as may be desired.

By loosening the set-screws, the slipper-bar may be moved forward or backward under the table in these guides, and when at the proper or desired point, fastened in position by again turning the set-screws, and the slippers thus adjusted, to conform to the position of the body, or to the different length of limb of different operators.

It is not intended to confine the invention herein claimed to the details of construction; but

What is claimed as the invention of the said JOHN H. C. COWGILL, is—

1. The combination; with a sewing-machine, of an inclined table or support, substantially as and for the purposes described.
2. The combination, with a sewing-machine, of a table or support that is movable or adjustable to any inclination desired, substantially as and for the purpose described.
3. The combination, with a sewing-machine, of an inclined top or support, and rests for the arms of the operator, substantially as and for the purpose described.
4. The combination, with a sewing-machine, of an

adjustable slipper-bar, substantially as and for the purpose described.

5. The combination, with a sewing-machine, of an inclined table or support, and an adjustable slipper-bar, substantially as and for the purpose described.

6. The combination, with a sewing-machine, of an inclined adjustable table or support, an adjustable slipper-bar, and rests for the arms of the operator, substantially as and for the purposes described.
